STEAM PURIFIER

Wilson L. McLaughlin, Herrold L. McLaughlin,
and Virg Ballou, Des Moines, Iowa

Application July 5, 1932. Serial No. 620,904

3 Claims. (Cl. 183—102)

The principal object of our invention is to provide a device capable of successfully removing undesirable foreign matter and small particles of condensed water from either low or high pressure steam.

A further object of this invention is to provide a steam purifier that requires no motive power for its operation.

A still further object of this invention is to provide a steam purifier for either low or high pressure steam that is economical in manufacture and durable in use.

These and other objects will be apparent to those skilled in the art.

Our invention consists in the construction, arrangement, and combination of the various parts of the device, whereby the objects contemplated are attained as hereinafter more fully set forth, pointed out in our claims and illustrated in the accompanying drawing, in which:

Fig. 1 is a side view of our complete device with a section cut away to illustrate its interior construction.

Fig. 2 is a cross sectional view of our steam purifier taken on line 2—2 of Fig. 1.

Fig. 3 is an inside view of a portion of the purifier housing illustrating one of the longitudinal vertical collecting grooves.

Fig. 4 is an enlarged top plan sectional view of a portion of the steam purifier housing for more fully illustrating the construction of the collecting grooves therein.

Many uses for steam in the commercial field today require that the steam be free of undesirable particles of foreign matter and water. The chief objections, however, to steam purifiers now being used for this purpose are their great cost and inability to successfully function with low pressure steam. We have overcome such objections as will be hereinafter appreciated.

Referring to the drawing, we have used the numeral 10 to designate the steam purifier housing of elongated cylindrical construction. The numeral 11 designates the steam inlet pipe passing through the center bottom of the housing 10 and extending upwardly in the center of the housing to the inside top of the housing, as shown in Fig. 1. The numeral 12 designates an opening in the side of the pipe and communicating with the inside of the housing 10. This opening 12 is positioned a slight distance above the inside bottom of the housing 10 and is designed to permit the steam from the pipe 11 to pass into the housing 10 near the inside bottom of the housing. The numeral 13 designates a baffle member inside the

pipe 11 and at the top of the opening 12 for closing the remaining portion of the pipe above the opening 12 against the steam and for guiding the steam out of the pipe 11 through the opening 12. The numeral 14 designates a spiral member embracing that portion of the pipe 11 inside the housing 12 with the pipe 11 acting as the core of the spiral member, as shown in Fig. 1 and Fig. 2. The outside diameter of this spiral conforms with the inside diameter of the housing 10.

The numeral 15 designates a plurality of spaced apart longitudinal vertical grooves formed in the inside circular wall of the housing 10. Each of these grooves have two sides, one side of which is at right angles to the inside face of the housing wall and the other side of which is at an angle thereto, as shown in Fig. 4. These grooves 15 extend approximately the entire inside length of the housing 10 and decrease in both width and depth as they extend upwardly.

The numeral 16 designates the steam outlet pipe leading from the inside top of the housing 10. The numeral 17 designates a water trap communicating with the inside bottom of the housing 10. The numeral 18 designates a water discharge pipe leading from the trap 17. This trap 17 is of the conventional type and as is well known, will pass collected water or like from the inside bottom of the housing 10, but will not pass steam.

The numeral 19 designates a manually operated valve interposed in the pipe 11 at a point before the pipe 11 enters the housing 10. The member 14 may spiral upwardly either to the right or left, but it is highly imperative that the grooves 15 be so designed accordingly in order that the steam travel will be directed toward the sides of the grooves that are perpendicular to the inside face of the housing 10. In Fig. 1, we show the member 14 spiraling upwardly to the right and therefore the sides of the collecting grooves perpendicular to the inside face of the housing are facing to the left or into the steam travel, as shown in Fig. 2. It will also be noted that the tapering of the width of the grooves does not affect the vertical plane of their sides that are perpendicular to the inside face of the housing. Such tapering, however, does affect the non-radially extending sides of the grooves.

The operation of our device for removing impurities from steam is quite simple. The valve 19 is opened for permitting the steam to be treated to pass through the pipe 11 into the inside bottom of the housing 10. The steam by its own pressure will rush upwardly to pass from

the housing through the outlet pipe 16. To reach the top of the housing the steam will be required to follow a spiraled path with the spiral member 14, resulting in the whirling or spinning of the steam. Naturally, all of the heavier particles in the steam stream, representing minute particles of foreign matter or water, will be thrown by centrifugal force to the outside of the stream and against the inside wall of the housing 10. These particles will collect and condense on the inside of the wall and in the grooves 15. The grooves and especially the radially extending sides of the grooves are ideally situated to contact and encourage the collecting of the particles. The cross sectional construction of the collecting grooves not only guides the undesired particles into their areas, but causes a certain amount of eddies which also encourage the collecting and condensing of the particles. Once the particles of water and dirt are trapped in the grooves they are protected from the action of the flow of steam and may move unhampered downwardly in the grooves to the bottom of the housing, from which they may be removed from time to time or may pass through the trap 17. As the steam passes upwardly it will become more free of such undesirable particles, while on the other hand, the particles in the grooves will increase as the grooves extend downwardly. It is for these reasons that our grooves 15 decrease in both depth and width as they extend upwardly. The steam, purified of undesirable matter and water, will pass from the device through the pipe 16.

Even low pressure steam will develop sufficient rapidity in its spiraling movement to the top of the housing for centrifugal force to act upon and remove impurities. If desired, the pressure of the steam and the rapidity of its passage through the device may be manually controlled by the valve 19.

Although our device is especially designed for the purifying of steam, it may be used to equal advantage in the purifying of other fluids.

45

50

60

65

70

75

Some changes may be made in the construction and arrangement of our improved steam purifier without departing from the real spirit and purpose of our invention, and it is our intention to cover by our claims any modified forms of structure or use of mechanical equivalents which may be reasonably included within their scope. 80

We claim:

1. In a device of the class described, a cylindrical upright elongated housing, a steam inlet pipe extending into the bottom of said housing, an outlet pipe communicating with the inside top of said housing, a spiral member in said housing for causing the steam passing through said housing to follow a spiral path, and a plurality of spaced apart longitudinally extending grooves in the inside face of said housing; said grooves each decreasing in depth and width as they extend upwardly. 85 90

2. In a device of the class described, an upright cylindrical housing, a pipe passing through the bottom of said housing and extending upwardly inside said housing to the inside top thereof; said pipe having an opening communicating with the inside of said housing near the inside bottom of said housing, a spiral member inside said housing and circling said pipe therein, a plurality of grooved passageways in the inside face of said housing, and an outlet pipe communicating with the inside top of said housing. 95 100

3. In a device of the class described, a cylindrical housing, a steam inlet pipe extending into said housing, a steam outlet pipe communicating with the inside of said housing, a spiral member in said housing for causing the steam passing through said housing to follow a spiral path, and a longitudinally extending groove on the inside of said housing decreasing in depth and width as it extends in one direction. 110 115
